UNITED STATES PATENT OFFICE.

HELMIT N. DAWSON, OF OAK HILL, KANSAS.

QUADRUPLE TIN-FOLDER.

SPECIFICATION forming part of Letters Patent No. 412,242, dated October 8, 1889.

Application filed June 16, 1888. Serial No. 277,300. (No model.)

To all whom it may concern:

Be it known that I, HELMIT N. DAWSON, a citizen of the United States, residing at Oak Hill, in the county of Clay and State of Kansas, have invented certain new and useful Improvements in Quadruple Tin-Folders; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to improvements in machines for folding tin and other material in sheet form for roofing and other purposes; and the objects are to construct a folder that shall at one and the same movement turn all four of the edges at one and the same time in a perfect manner and ready for immediate use. I attain these objects by means of the mechanism hereinafter described, and illustrated in the accompanying drawings, in which—

Figure 1 is a plan of my machine; Fig. 2, a front elevation, having a part of the frame, the crank, and foot-treadle removed. Fig. 3 is also a front elevation, with tin plate removed and upper platen raised.

Similar letters refer to similar parts throughout the several views.

My machine consists of the frame A, table or bed B, lower platen C, with bevel-edge α and bending-levers $r r$ hinged to the sides thereof and actuated by the connecting-rods D D; upper platen G, having bevel-edges $k k$ and bending-levers $e e$, hinged to the sides thereof and actuated by the connecting-rods E E, the several connecting-rods D D and E E being adjustable by means of the slots $f f$ and bolts $i i$; the standard F, head H, with guide-piece p sliding in the housing I, which is supported by braces J J from the frame; the standard-brace o ; plate K, having notched inclined slot n , lever L, bracket m , eccentrics $c c$, firmly secured to the shafts a and b , and having adjusting-holes $y y$ and pins $z z$. The shafts a and b are both in the same plane, and on them are mounted the bevel-gears g and h in contact with each other. The shaft a is U-shaped opposite

the shaft b . The crank d is secured to the shaft b and connected by the rod e with the foot-treadle raised by the spring s .

1, 2, 3, and 4 are guide-pins passing through holes in the bending-levers, and 5 a sheet of tin or other material in position to be folded.

The lower platen C is immovably secured to the table or bed B. The upper platen G is attached to and raised and lowered by the standard F, which is secured to the lever L, the lever L being pivoted at one end to the bracket m and held in position by engaging the ratchet-teeth in the plate K. The platen G is raised or lowered by the lateral moving of the lever L, the incline to the slot n giving the vertical movement to the standard F. When lowered, the standard F is steadied in its position by coming in contact with the braces o and J , substantially as shown.

When used as a double folder only, it may or may not be necessary to avoid the action of two of the bending-levers by detaching them from their respective rods. It will not be necessary if the sheet to be folded be no wider one way than the platen itself. For instance, if the machine be constructed to fold the four edges of a sheet twenty by twenty-eight inches, two edges of a sheet eighteen by twenty-eight inches could be folded without detaching the bending-levers.

It will readily be seen that the foot-treadle may be removed and the machine worked by hand by means of the crank d , if preferred.

Having thus described my invention, what I claim as new, and desire to secure by Letters Patent, is—

In a folder, the combination, with the stationary and movable platens having bending-levers hinged to the sides thereof, of a standard secured to the upper platen, a lever connected with said standard, and a plate having an inclined toothed slot receiving one end of said lever, whereby the lateral movement of the lever in said plate imparts a vertical movement to the standard and movable platen, substantially as described.

In testimony whereof I affix my signature in presence of two witnesses.

HELMIT N. DAWSON.

Witnesses:

W. A. HOWARD,

HY. W. STACKPOLE.
